UNITED STATES PATENT OFFICE.

LINNAEUS E. BAKER, OF FORT WAYNE, INDIANA, ASSIGNOR TO WAYNE OIL TANK AND PUMP COMPANY, A CORPORATION OF INDIANA.

COUNTER FOR DISPENSING APPARATUS.

1,286,200.

Specification of Letters Patent.

Patented Dec. 3, 1918.

Application filed December 11, 1915. Serial No. 66,272.

To all whom it may concern:

Be it known that I, LINNAEUS E. BAKER, a citizen of the United States of America, and resident of Fort Wayne, in the county 5 of Allen and State of Indiana, have invented certain new and useful Improvements in Counters for Dispensing Apparatus, - of which the following is a specification.

This invention relates to improvements in 10 counters for dispensing apparatus and is intended especially as a means of indicating to purchasers of the goods being dispensed the precise quantity in units of measurement as the same is delivered by the apparatus. 15 A further object is to provide a device of the kind that will show conspicuously by indicated numerals the quantity of goods as the same are dispensed by the apparatus, and also to construct the counter so that its index 20 may be readily reset by the operator to the point of commencement without interference with the operation of the dispensing apparatus.

The above objects are accomplished by 25 the construction illustrated in the accompanying drawings in which:-

Figure 1 is a front elevation of the device and a portion of a dispensing apparatus to which it is attached;

30 Fig. 2 is a vertical central section of the counter in a plane at right angles to that of Fig. 1, an adjacent portion of the housing of the dispensing apparatus being included;

Fig. 3 is a side view of Fig. 1; and

35 Fig. 4 is a detailed view showing a vertical section of the counter on the line α - α of Fig. 1 including adjacent portions of the dispensing apparatus.

Similar characters of reference indicate 40 corresponding parts throughout the several views and the following specification refers to the various parts by the same characters:

The present invention is constructed so as to be applied to a pump of that class usually 45 employed in dispensing gasoline, oils and other liquids, and especially to that type of pump that has in its construction a reciprocating rack-bar (A) by means of which the pump is actuated. The pump proper is not 50 included in the illustrations, but a portion of the actuating mechanism for the pump is included in order to show the application of the invention thereto. The construction of the pump mechanism to which the present 55 invention may be applied, may be in various

forms, and the construction of the pump mechanism herein shown is given as an example of the type of pump mechanism with which the invention may be employed.

The pump shown has a reciprocating rack-bar (A) that is ordinarily used for actuating the pump proper, and a pinion (B) is arranged in mesh with the rack-bar for transmitting movement thereto. The pinion is fixed upon a countershaft (C) that has 60 also fixed thereon a back-gear (D). The shaft (C) is rotatively mounted in a housing (E) designed to inclose the gearing of the pump. A drive-shaft (F) is also mounted in the housing and has fixed thereupon a driving pinion (G) that meshes with the back-gear (D), and has also fixed thereupon a crank (H) by means of which the drive-shaft is actuated.

The mechanism thus described is of 75 known construction and is of a type to which the present invention is applicable.

The invention is comprised of a dial (J) of circular form, bearing upon its outer face an annular series of indicating numerals, 1, 80 2, 3, etc., and having associated therewith a movable index (K) and mechanism actuated by the reciprocating rack-bar of the pump for progressing the index to its various indicating positions successively accordingly 85 as the pump is actuated. The dial is secured in the front of a case (L) that has an internal partition (M) therein through which a securing bolt (N) extends and by means of which the case is fixed to the housing (E). A rotating member (P) having a boss (Q) upon one side thereof, and an internal annular series of notches (R) upon the opposite side, is mounted within the case 90 between the dial and partition and with its boss extending through the dial. The index (K) is fixed to the outer end of the boss by means of a screw (S) so that the rotating member and index will revolve together. Upon the bolt (N) between the partition 100 (M) and the housing (E) is mounted a bell-crank (T), the horizontal arm of which extends outwardly through a slot (U) in the side of the case and has pivoted at its outer end a pawl (V) having a detent pin (W) 105 projecting therefrom and adapted to engage the arm of the bell-crank so as to limit its swinging movement relative to the arm. The other arm of the bell-crank has fixed thereto a pin (X) that extends through an 110

elongated opening (Y) in the partition (M) of the case, and has loosely mounted thereon a ratchet (Z) that is adapted to engage the notches (R) in the rotating member and 5 drive the latter as the bell-crank is actuated. The case (L) is held from rotating upon the bolt (N) by a screw (L') that extends through the partition (M) and into the housing so that the opening in the partition 10 and also the dial on the outer face of the case will be held at all times in proper position.

Upon the outer end of the counter-shaft is fixed an actuating member (C') having 15 two oppositely disposed lugs (C'') that are adapted severally to engage and lift the pawl (V) and become disengaged after lifting the same as the counter-shaft (C) is rotated in one direction. The pin (W), by 20 contacting with the horizontal arm of the bell-crank (T) prevents the pawl from being turned out of the path of the lugs when the actuating member is being rotated in one direction. Thus, as the lugs bear upwardly 25 against the lower end of the pawl during the rotation of the counter-shaft, the bell-crank is accordingly actuated, and through the medium of the ratchet (Z) the rotating member (P) and index fixed thereon are 30 progressed from one stage to another successively as the bell-crank is actuated. The pumping mechanism, being of the type that effects the discharge of liquid only upon the rising movement of the rack-bar (A), it is 35 essential that the bell-crank be actuated during the upward stroke of the rack-bar, and it is also essential so that the index will become progressed more or less as the discharge from the pumping mechanism takes 40 place. It is also essential that as the movement of the counter-shaft is reversed and the rack-bar accordingly is driven through its downward movement, during which no 45 discharge of liquid from the pumping mechanism takes place, that the index shall therefore remain inert. During the reverse movement of the counter-shaft the lugs of the actuating member in bearing against the

adjacent face of the pawl have the effect of swinging the pawl upon its pivotal support 50 out of the path of the lugs so that the bell-crank remains inert.

Of course, it is necessary to proportion the mechanism and arrange the indicating numerals to suit the length of the stroke of 55 the rack-bar and the quantitative discharge of the pumping mechanism in its cycle of movement.

In the operation of the invention the pumping mechanism is manipulated by actuating the crank (H) so that the rack-bar reaches the point of commencement of its upward or discharge stroke and the index is manually turned to the point at the commencement of its cycle, as at (O). The 60 crank is then actuated so that the pumping mechanism is operated in the customary manner and during the upward stroke of the rack-bar or while the discharge of the pump takes place the index, through the medium 65 of the mechanism described, becomes progressed upon each actuation of the bell-crank from one indicating numeral to the other, thus signifying in plain view of the purchaser the precise quantity of liquid in 70 units of measurement the amount of liquid 75 being discharged as the operation progresses.

What I claim is:—

In a device of the class described, a case having a round chamber therein; a cylindrical toothed rotating member located in the chamber with its external peripheral surface bearing against the inner peripheral wall of the case; a fixed dial holding the rotating member within the case, and having a central opening; an index having fixed relation through the opening with the rotating member; and actuating means for progressing the rotating member.

In testimony whereof I affix my signature 90 in presence of two witnesses.

LINNAEUS E. BAKER.
